JEAN BAPTISTE THEOPHILE ADRIEN LEGRAND, OF PARIS, FRANCE, ASSIGNOR TO
SOCIÉTÉ ADRIEN LEGRAND ET CIE., OF PARIS, FRANCE.

SCAVENGER FOR WATER OF CONDENSATION.

Application filed March 12, 1924. Serial No. 699,815.

This invention relates to scavenging or ejecting apparatus for removing water of condensation.

The apparatus, according to the invention 5 functions by rectilinear or longitudinal expansion of the tubing to which the device is connected, which tubing is free to expand and contract longitudinally and open at the end for the passage of steam, the closure 10 being effected by means of a relatively fixed obturating device located opposite to and beyond the opening of the tube independent of such tube and against which obturating device the scavenging or ejecting nozzle is 15 brought by the rectilinear or longitudinal expansion caused by the passage of steam through the said tubing preferably provided with a nozzle at its end.

In order that the invention may be clearly 20 understood, it will now be described with reference to the accompanying drawing, which shows scavenging or ejecting apparatus constructed according to the invention.

Fig. 1 is a longitudinal section of the apparatus with the obturating device carried by a bar or the like cemented into a wall.

Figs. 2 and 3 are respectively a front elevation and a plan illustrating a modification, in which the obturating device is carried by 30 a frame cemented into the ground.

The apparatus according to the invention comprises essentially a fixed part and a part adapted to be displaced through the effects of expansion.

The fixed part comprises an iron bar or the like 1 cemented to a wall, as shown in Fig. 1 or carried by a framework 1^a cemented into the ground, as shown in Figs. 2 and 3.

40 The bar or frame carries a screw threaded rod 2, the position of which is longitudinally adjustable with respect thereto by means of the two nuts 3—3 and the helical spring 4, compressed by the nut 5.

45 The screw threaded rod 2 has integral therewith a hexagonal head 6, provided with a socket joint in which engages the stem 7 of a conical valve 8. In order to prevent the stem 7 of the valve from leaving the head 6, 50 the pin 9 is passed through the nut portion of said head and engages in a channel 10 formed in the stem 7.

55 It is of course obvious that the conical valve 8 could be replaced by a spherical or other appropriately shaped valve.

The movable part which is adapted to be displaced under the influence of the expansion comprises a hollow cylindrical body 11 secured to the end of the tubing 17 into which screws a member 12 which is short, 60 and is provided with a conduit or passage 13. The end 14 of the member 12 is so formed and located as to constitute a valve seat adapted to fit closely against the conical valve 8 of the fixed part. The opposite end 65 of the member 12 is screw threaded for the reception of a sleeve 16 which is intended to connect the body of the scavenging or ejecting apparatus to the extremity of the tubing 17 through which the water passes from the 70 apparatus to be scavenged.

18 is a nipple for removing the scavenged water connected by a sleeve 19 to an outlet pipe 20.

In order to render the body 11 steam and 75 water tight, the said body is provided with a tubular piece 21 screwed into the same. Through this piece the stem 7 of the valve member is adapted to pass. 22 are packing rings, 23 is a pressure ring, and 24 a screw 80 cap.

The bar 1 of the frame 1^a is mounted or cemented in position so as to allow for longitudinal displacement of the body 11 of the scavenging or ejecting apparatus longitudinally along the valve stem 7. This displacement is equal to the expansion in a rectilinear or longitudinal direction of the scavenging tube. It follows that when the steam supply is opened, the steam forces all the 85 water of condensation contained in the system forward and it is easily removed through the orifice 14 and the outlet pipe 20.

90 After the water of condensation passes away, the steam causes the expansion in 95 length of the straight portion of the tubing 17; and when it reaches its maximum length, the seat 14 comes against the conical valve producing a hermetic closing of the same.

The valve has of course been so set and 100 regulated previously by means of the nuts 3 and the spring 4 that this operation can take place, the said spring 4 being slightly compressed when the steam is at its highest pressure and consequently at its highest 105 temperature.

When a small quantity of water accumulates against the conical valve 8, it cools the extremity of the tubing 17, so that there is a very slight contraction, which permits of the 110

automatic and continuous evacuation of the water of condensation accompanied by a very small stream of steam.

I claim:—

- 5 1. Mechanism for automatically discharging water of condensation from steam pipe lines, comprising a steam pipe for receiving water of condensation, a vented casing connected to said steam pipe, a valve seat at 10 one end of the casing; an alined valve in the opposite end of the casing co-operating with said seat, and means separate and independent of the casing and the pipe line to which said casing is connected to hold the valve 15 stationary and uninfluenced by steam of the pipe line, said casing moving with respect to the valve solely by the expansion and contraction of the pipe line to which the mechanism is connected.
- 20 2. Mechanism for automatically discharging water of condensation from steam pipe lines, comprising a steam pipe for receiving water of condensation, a vented casing connected to said steam pipe, a valve seat at 25 one end of said casing, an alined valve in the opposite end of the casing cooperating with said seat, means separate from the casing and the pipe to which said casing is connected, to hold the valve stationary and 30 uninfluenced by the steam of the pipe line, and means to adjust said valve to and from the seat, said means being uninfluenced by the steam from the pipe line.
- 35 3. Mechanism for automatically discharging water of condensation from steam lines, which comprises a casing having a discharge orifice, a valve seat in one end of the casing arranged for connection to a steam pipe, an alined valve in the opposite end of the casing, 40 cooperating with said seat, means independent of the casing to support the valve, and means to permit lateral deviation of the valve with the casing when the latter deviates from a straight line with the pipe to 45 which it is to be connected.
- 45 4. Mechanism for automatically discharg-

ing water of condensation from steam lines, which comprises a short tubular casing having a discharge orifice, a valve seat rigidly secured in one end and arranged for connection to a steam pipe, an alined valve in the opposite end of said casing cooperating with said seat, a support for said valve independent of said casing, means at said support to adjust the valve to and from the seat, means to permit the valve to automatically displace upon excessive closing movement of the seat, and means to permit the valve to laterally move with the casing.

5. Mechanism for automatically discharging water of condensation from steam lines, which comprises a short, tubular casing, a valve seat secured in one end, arranged for connection to a steam pipe, and having a discharge orifice, a valve in the opposite end 65 of said casing having its stem projecting from the casing, a support separate from said casing, a screw-threaded rod passing through the support, a nut on the rod, a spring between the nut and support and 70 means movably connecting the ends of the rod and stem.

6. A scavenging or ejecting apparatus comprising a movable, expansible part comprising a steam tube for receiving water of condensation; a stationary element opposite said tube and fixed at a point independent of, separate from and located outside the tube; a valve carried by the stationary element, a stem carrying the valve, a socket joint for the valve stem, a screw-threaded rod carrying said joint the position of which rod can be adjusted with respect to said stationary element, a scavenging body carried by the movable part and sliding upon the 80 stem of the valve, a valve seat provided in said body for said valve, and a discharge nozzle for the water of condensation carried by the body of the scavenging apparatus.

In testimony that I claim the foregoing 90 as my invention, I have signed my name.

JEAN BAPTISTE THEOPHILE ADRIEN LEGRAND.
